(57) **CLAIM**

The ornamental design for a remote dog trainer, as shown and described.

DESCRIPTION

FIG. 1 is a top front perspective view of a remote dog trainer showing my new design;

FIG. 2 is another perspective view of the remote dog trainer at an offset angle with respect to FIG. 1;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view thereof, as labeled with symbol 9 in FIG. 1; and,

FIG. 10 is another partial enlarged view thereof, as labeled with symbol 10 in FIG. 8.

The broken lines immediately adjacent to the claimed portions are boundaries, the broken lines form no part of the claimed design.

1 Claim, 10 Drawing Sheets
